CORE DRILL

Albert F. Pickard, Minneapolis, Minn., assignor to
 E. J. Longyear Company, Minneapolis, Minn.,
 a corporation of Delaware

Application November 15, 1948, Serial No. 60,093

5 Claims. (Cl. 255—72)

1

This invention relates to core barrels used with core drills, particularly of the type used for exploratory drilling, and more especially to improvements in core lifters for such core barrels. In the art of core drilling the bit, reaming shell, core barrel outer and inner tubes, core lifter and couplings, by which the assembly is attached to the drill rods are collectively known as the "core barrel."

In the core drilling art it has been common practice to provide a core barrel with a core barrel inner tube for receiving the core as it is produced by the drill. As originally made such barrels had the core barrel inner tube mounted so as to rotate with the outer tube, but these were subject to objection because the rotating core barrel inner tube tended to jam or drag upon the core as it was produced, and in many instances caused the core to be disintegrated, thus destroying or limiting the usefulness of the mechanism for exploratory work.

More lately, it has been the practice to mount the core barrel inner tube upon journals so that the core barrel inner tube is free to receive the core as it is produced, without itself rotating. The effect is that the core barrel inner tube, as it drags slightly upon the core, is thereby stopped from rotating, the outer tube of the assembly in the meantime being free to rotate about the core barrel inner tube as the entire mechanism progressed into the formation being drilled.

For the purpose of breaking loose the core when the core barrel inner tube is filled, it has been customary to provide what is known as a "core lifter" in the core barrel assembly. This is usually in the form of a small split ring having an exterior tapered or conical surface which bears upon a corresponding surface of the drill bit and an interior surface for gripping the core thereby to break the core when the core barrel is withdrawn.

In most instances the core lifter has been mounted in a recess in the bit itself, but such a method of mounting has been subject to disadvantages because the rotating bit tends to rotate the core lifter, and as a result the core lifter wears the core and tends to disintegrate it. In other instances, attempts have been made to mount the core lifter upon the core barrel inner tube, when the latter is journalled, so as thereby to provide non-rotation of the core lifter as the core barrel progresses forward over the core. The difficulty with such constructions has been that the core barrel inner tube, and particularly its journal mounting, are not sufficiently strong to provide the tension force necessary for break-

2

ing a strong core formation. As a result, journals and the core barrel inner tubes have been broken when attempts are made to withdraw the core barrel and the core, when using such mechanisms. Also, the core barrel inner tube is of thin metal and it is difficult to machine threads into the end of it. Hence, attempts to mount the core lifter on the core barrel inner tube have necessitated a thickening of the inner tube or, conversely, acceptance of a weak inner tube structure.

It is an object of the present invention to provide an improved core barrel wherein the foregoing disadvantages are obviated and more particularly to provide an improved core barrel wherein the core lifter is mounted in such a manner that during the drilling operation it is carried by and assumes a position on the lower end of the core barrel inner tube and accordingly has a non-rotating action during this portion of its operation, but is mounted so as to transfer the loading imposed by breaking and lifting the core to the bit during the core breaking and withdrawing function.

It is also an object of the invention to provide an improved core barrel wherein the core lifter is mounted within a transfer case slidable upon the core barrel inner tube and movable relative thereto into abutment with the bit for breaking and lifting the core.

It is a further object of the invention to provide an improved core barrel capable of extracting a much larger percentage of core than has been possible with previous apparatus.

It is also an object of the invention to provide an improved core barrel of rugged and simple construction, yet having improved functioning characteristics.

Other and further objects of the invention are those inherent in the apparatus herein illustrated, described and claimed.

The invention is illustrated with reference to the drawings wherein

Figure 1 is a longitudinal view, partly in section, of the core barrel of the present invention showing it during the period of drilling;

Figure 2 is a fragmentary longitudinal sectional view of the core lifter portion and bit end of the apparatus shown in Figure 1 and showing the apparatus during the core lifting operation;

Figure 3 is a longitudinal sectional view somewhat enlarged as compared to Figures 1 and 2, showing the transfer case separated from the remaining portions of the apparatus;

Figure 4 is a longitudinal sectional view of the core lifter which operates in conjunction with the transfer case of Figure 3, likewise shown separated from the remaining portions of the apparatus;

Figure 5 is a longitudinal sectional view of a modified form of core lifter for soft cores, which also may be used in the transfer case of Figure 3, in place of the core lifter of Figure 4.

Referring to the drawings 10 illustrates the earth or rock formation through which the drill is being penetrated for producing a core 11 of the formation. The core barrel includes a coupling 12 which is provided at its upper end with standard threads 13 for receiving the lower coupling of the drill rods to which it is attached. The coupling 12 is bored to receive an inner member 8 which is press fitted into the coupling 12 and additionally pinned at 9 to provide a solid connection. The member 8 is provided with a channel at 15 which terminates at the space 16 so as to allow the drilling fluid to travel in the direction of arrows 17 for cooling the bit, and the coupling 12 and member 8 are side drilled at 7 to provide a relief port extending into the center bore 6. The member 8 is provided with a screwed in tubular journal stud 18 which is threaded into the member 8 and provided at its lower end with a portion 19 of reduced diameter. Upon the portions 18 and 19 there is journalled the journal block 20 of the core barrel inner tube 27. The journal block 20 is held between the bearing washers 21 and 22 and is retained in place by means of the castellated nut 23, the latter being adjusted and held by cotter pin 24. The member 20 is provided with threads at 25 so as to receive the upper threaded end of the core barrel inner tube 27. As a consequence of this construction the core barrel inner tube 27 and journal block 20 are free to rotate as a unit relative to the stud 18-19, or stated conversely, the core barrel inner tube 27 can remain stationary and slide down upon the core while the outer tube 31, reaming shell 33 and bit 35 rotate as a unit around it.

Upon the exterior surface of the member 12 there are provided threads 30 to which there is attached the upper end 31 of the outer tube. The lower end of the outer tube is threaded at 32 so as to receive the upper end of the reaming shell 33 which likewise is threaded at its lower end 34 to receive the bit 35. Consequently, as the coupling 12 is rotated during the drilling operation, core barrel outer tube, reaming shell 33 and bit 35 are likewise rotated. The lower surface of the bit 35 and the outer surface of the reaming shell 33 are provided with inset diamonds, bort, stellite or other hard cutting material, and consequently as the unit is rotated, the bit 35 gradually drills into the surface 37 and the bit forms the core 11. Meanwhile the core barrel inner tube 27 drags upon the core 11 and consequently it is held from rotation, this being permitted by the journaling action on the journal stud 18-19.

The lower end of the core barrel inner tube 27 is provided with a female shoulder at 38 into which there projects the correspondingly sized male end 39 of the inner tube extension 40. The junction 38-39 is a press fit and the member 40 accordingly forms the lower end of the core barrel inner tube 27 which can, however, be removed when worn out. The members 40 and 27 may be made integral in accordance with the present invention, since the two members 40 and 27 act as a unit.

The lower end of member 40, which is actually the lower end of the core barrel inner tube, has a male portion 41 of reduced diameter upon which the correspondingly sized female portion 42 of the transfer case, generally designated 43, is adapted to slide longitudinally. Referring to Figure 3 it will be noted that the transfer case 43 has a uniform outer diameter 45 and an upper cylindrical portion 44 of uniform diameter. At the lower end of the transfer case there is an internally tapered conical surface 46, the two surfaces 44 and 46 being separated by an internally extending flange 47. The lower edge 48 of the transfer case is provided with a plurality of notches 49 across which the drilling fluid may pass so as to allow the drilling fluid to drain when the drill string is lifted.

Referring to Figure 4 there is illustrated a core lifter generally designated 50 having an internal longitudinally fluted surface 51 and an outer surface 52 of tapered conical configuration adapted to fit and slide upon the be wedged to smaller diameter by the internal conical surface 46 of the transfer case. The core lifter 50 has a split at 54 so as to permit it to assume a shape of smaller diameter, as is common practice.

Referring to Figure 1, during the drilling operation the transfer case 43 which contains the core lifter 50 moves relatively upwardly as a unit. This movement is due to the fact that the core lifter 50 slightly grips upon the core 11 and hence as the outer tube, bit and reaming shell gradually move downwardly, the core lifter 50 tends to drag upon the core 11 and tends to push against the under surface of the flange 47 of the transfer case, thereby likewise causing the transfer case to drag upon the core. Since the core barrel inner tube, although not rotating, still moves axially with the outer tube, the lower end 41 of the core barrel inner tube slides in the female portion 42 of the transfer case until the lower end of the core barrel inner tube abuts against the upper surface of flange 47. Thereupon, the transfer case 43 and core lifter 50 are moved downwardly as a unit upon the core 11 but neither rotates and the inner tube 27 likewise does not rotate. During this time it will be noted that there is a space at 55 between the lower edge 48 of the transfer case 43 and the inner ledge 58 of the bit 35. Hence, the drilling water or fluid entering via arrow 17 is permitted to cross this space, as illustrated by the arrow 59 and crosses the face of the bit.

When the core 11 has filled the core barrel inner tube 27, the entire drill string rotation is stopped and a lifting force is applied thereto. The first action is to lift the bit 35 off the bottom of the hole, as shown in Figure 2, and then as the bit is withdrawn the inner shoulder 58 of the bit 35 comes into contact with the lower surface 48 of the transfer case, which in in the meantime has remained stationary due to its drag upon the core. As the drill string and bit 35 was lifted, this likewise lifted the core barrel inner tube 27 and the transfer case 43, being retained by the gripping action of the core lifter 50, hence slides relative to the lower end of the core barrel inner tube at the junction 41-42. As additional lifting force is applied on the bit the transfer case is lifted upwardly, the core lifter 50 in the meantime being held by its grip upon the core. The relative movement of the transfer case upwardly outside the core lifter 50 thereby contracts the core lifter due to the wedging action of the cooperating conical surfaces 46 and 52. When a sufficient lifting force has thus been applied to the core 11

it is broken off as illustrated at 60 and the entire core barrel and drill string is then withdrawn and removed from the hole.

When the core barrel is used in very soft formations, such as clay, the core lifter 50 of Figure 4 may be replaced by the core lifter assembly 70 of Figure 5, wherein the ring 71 is flexible and is split at 72. The outer surface of the ring 71 is tapered at 73 to correspond to the taper 46 of the transfer case 43, but the inner surface of 71 is notched at its upper edge to receive a plurality of flexible inwardly bent fingers 75 which are firmly attached to the ring 71 by rivets 76. The entire assembly 70 fits into the transfer case 43 and operates like the core lifter 50 in that while drilling is proceeding, it remains stationary and hugs the core as the latter is produced, meanwhile forcing the transfer case relatively upwardly against the core barrel inner tube as in Figure 1. When the core barrel is withdrawn the transfer case is lifted by contact with surface 58 of the bit, the core lifter meanwhile hugging the core. As more lifting force is applied the fingers 75 dig into the core and break it. If perchance the lifter of Figure 5 should be in the core barrel and the formation should turn out hard instead of soft, no harm results since the fingers are merely flexed out and inner surface 71 then grips the (hard) core as is the case with the core lifter 50 of Figure 4.

As many apparently widely different embodiments of this invention may be made without departing from the spirit and scope thereof, it is to be understood that I do not limit myself to the specific embodiments herein.

What I claim is:

1. In a core barrel having an annular drill bit and having an inner tube journaled within the drill string, said inner tube terminating in spaced relation to the bit for receiving the core as it is produced, the improvement comprising a slideable tubular transfer case shaped to slide axially upon that portion of the inner tube which is most adjacent the bit and having an axial length such that it is free to move axially between the bit and adjacent end of the inner tube, said case being shaped so as to abut against the bit when moved axially toward the bit and abut against a part of the inner tube when moved axially toward the inner tube so as thereby to have only a limited range of axial movement, said case having a tapered inner surface between the end of the inner tube and the bit, and a split core lifter ring having an inner surface for engaging the core and a

tapered outer surface for engaging the tapered inner surface of the transfer case.

2. The apparatus of claim 1 further characterized in that the transfer case has an inwardly extending flange adjacent that portion of its inner tapered surface which is of maximum diameter.

3. The apparatus of claim 1 further characterized in that the core lifter has spring fingers extending upwardly and inwardly therefrom for gripping the core.

4. In a core barrel having an outer tube provided with a reaming shell and terminating in an annular drill bit and having a core barrel inner tube of lesser diameter than the outer tube, journaled at one end in the outer tube and having a free end, the improvement comprising having the core barrel inner tube of a length such that a space is provided between the free end of the core barrel inner tube and the drill bit, and a cylindrical transfer case of approximately the same diameter as the core barrel inner tube fitted to the free end of the inner tube for limited axial sliding movement thereon and having an axial length such that it is free to move between the bit and the adjacent end of the inner tube, said transfer case being free to rotate with respect to the core barrel inner tube, said transfer case having a tapered conical inner surface and a split core lifter ring having a conical external surface fitted to slide within and be contacted by the tapered conical inner surface of the transfer case, said core lifter ring and transfer case being axially slideable as an assembly on the core barrel inner tube from a position spaced from the bit to a position in abutment with the bit.

5. The apparatus of claim 4 further characterized in that the core barrel inner tube slides within a portion of the transfer case and said transfer case has a flange on its inner surface to serve as a stop for said sliding movement and as a stop for the sliding movement of the split lifter ring therein.
